UNITED STATES PATENT OFFICE.

CHARLES C. SMITH, OF CLAREMONT, NEW HAMPSHIRE, ASSIGNEE TO SULLIVAN MACHINERY COMPANY, A CORPORATION OF MASSACHUSETTS.

SAFETY APPARATUS.

Application filed December 11, 1920. Serial No. 430,102.

My invention relates to safety apparatus.

It has for its object to provide improved means for arresting a rearward movement of an object, and more especially a downward movement on a pitch or incline. A further object of my invention is to provide improved means adapted to cooperate with a part of a gallery upon a rearward movement of an object, and through leverage actuated upon this rearward movement bring the latter into frictional contact with the gallery in such a manner as to arrest its movement. A further object of my invention is to provide improved means of the character set forth which, while automatically retained in "ready" position and automatically operative to arrest, without damage to the bottom or track, a rearward movement of an object on which it is carried, enables the object to be moved forward whenever desired and without damage to the roof. These and other objects and advantages of my improved construction will, however, hereinafter more fully appear.

25 In the accompanying drawings I have shown for purposes of illustration one embodiment which my invention may assume in practice, the same being illustrated as applied to use in connection with a mining machine.

30 In these drawings,—

Fig. 1 is a plan view of the mining machine equipped with my improvement.

Fig. 2 is a side elevation of the rear end 35 of the machine, my improved safety means being shown in a plurality of positions.

Fig. 3 is a diagrammatic view showing the machine in side elevation and operating on a pitch.

40 Fig. 4 is a detail sectional view on line 4—4 of Fig. 2.

The mining machine shown is of the long-wall type, having a frame 1 and a cutter bar 2. The latter herein carries a usual cutter chain 3 and is pivotally connected to one end of the frame and held as desired, either in opposite lateral positions or in a longitudinal position, by a removable pin 4 cooperating with registering recesses 4' in the frame and bar. A suitable feed operating member 5 is also rotatably mounted on the other end of the frame and adapted to cooperate with a flexible feeding member of any suitable form, herein in the form of a feed chain 6 suitably guided by guiding sprockets 7. As

in a usual construction, both the cutter chain and the feed operating member are also driven from the motor 8 of the mining machine through usual connections, not shown. In the use of such a machine, the bar is 60 swung in under the face in any suitable manner, as for instance by connecting the feed chain to projections 9 on the bar and then simultaneously operating the cutter chain 3 and feed operating member 5. The chain is 65 then extended along the face and anchored so that when the feed operating member 5 and the cutter chain 3 are again simultaneously operated, the machine will be fed along the feed chain and the face and occupy the 70 position illustrated in Fig. 1 during its transverse cutting operation.

In my improved construction, I have provided at a suitable point on the machine, automatic means adapted to engage a part of 75 the mine gallery when the machine, for any reason, starts backward down a pitch, and, through its engagement with the gallery, adapted instantly and positively to arrest the downward movement of the machine on 80 the pitch. These means may obviously assume various forms. In the illustrative form shown, however, it will be noted that they include a sprag 10 suitably mounted on the mining machine, herein at the rear thereof, and extending upwardly therefrom. Herein, this sprag is mounted on a transverse pivot 11 and the pivot 11 is in turn carried on an upright 12 rigidly connected to the frame of the machine and disposed between the machine shoe 13 and an overlying portion 14 of the frame. As shown in Fig. 4 this upright is in the form of a sleeve held in position by a removable bolt 15 threaded at its lower end into the shoe 13 and extending upward through the central opening 4' for the pin 4, suitable removable flanged bushings 16 cooperating to locate the bolt properly in the opening 4'. This sprag 10 is, as shown, of such length as to enable its 90 upper end, preferably pointed and rounded as shown at 17, to engage with the roof and follow the surface thereof as the machine is moved forward. Herein, it is also operatively connected with the frame portion 14 95 by a suitable yielding connection herein in the form of a relatively light spring coil 18 operatively connected between a collar substantially mid-way between the ends of the sprag and a point at the rear end and on the 100 105 110

top of the frame, although obviously the point of connection of the spring and the sprag may be varied by adjusting the collar. As a result of this spring connection, it will be observed that the sprag is normally held in the rearwardly inclined position shown in dotted lines in Fig. 2.

In the operation of my improved construction, when, through the cooperation of 10 the feed operating member 5 and the flexible feed member 6, the machine is cutting up a pitch, the sprag 10 will always tend to occupy the dotted line position mentioned, its upper end following the roof surface and 15 the sprag through the action of the spring 18, freely yielding to enable it to pass all obstructions and yet instantly swinging back into "ready" position. When, however, for any reason, the machine starts back, i. e. 20 down the pitch, the rearward movement of the same moves the sprag pivot bodily rearwardly in such a manner as to drive the upper end of the sprag into the roof and form a toggle which at the same time that it drives 25 the sprag deeper into the roof presses the machine against the bottom and thereby promptly and effectually prevents further slipping of the machine and the resultant damage to the men and equipment which 30 would otherwise result.

As a result of my improved construction, it will be observed that it is possible to arrest the rearward movement of an object without damage to the bottom or track upon 35 which the object moves and that it is further possible to permit the object to move forward at any time without damage to the roof, the toggle action of the sprag during the rearward movement tending simply to 40 press the object against the bottom, and the spring connection of the sprag enabling it, during forward movement, to clear obstructions such as timbering, or the like, without damage to the roof. It will also be evident 45 that whenever it is desired to permit a free rearward movement of the object, the sprag may be readily rendered inoperative by simply disconnecting the spring and the sprag pivot. In certain instances where the bottom 50 is relatively smooth, disconnection of only the spring will be sufficient, as the rounded end of the sprag will enable it to ride over the bottom in rear of the rearwardly moving object.

55 While I have herein specifically described one embodiment of my invention, it will be understood that this form of the same is shown for purposes of illustration and that the invention may assume different forms 60 and may be adapted to different uses other than in connection with a mining machine without departing from its spirit or the scope of the appended claims.

65 What I claim as new and desire to secure by Letters Patent is:

1. The combination with a self-propelled mining machine bodily slidable on its own bottom on the mine bottom during cutting, and means for continuously feeding the machine during cutting, of means carried by 70 and movable at a uniform rate with said machine normally adapted to yieldably engage a mine roof during forward feeding movement and to positively engage the mine roof during reverse movement to arrest said 75 machine.

2. The combination with a self-propelled mining machine bodily slidable on its own bottom on the mine bottom during cutting, and means for continuously feeding the machine during cutting, of means movable at a uniform rate with the machine including a sprag pivoted on said machine adapted to normally yieldably engage with the mine roof during forward feeding movement and 80 to positively engage the mine roof during reverse movement to arrest said machine.

3. The combination with a self-propelled mining machine bodily slidable on its own bottom on the mine bottom during cutting, and means for continuously feeding the machine during cutting including a flexible element, of means carried by said machine and movable at a uniform rate therewith adapted to normally yieldably engage the mine roof during forward feeding movement and 85 to positively engage a mine roof during reverse movement due to failure of said flexible member to arrest said machine.

4. The combination with a mining machine freely slidable in one direction on the mine bottom during cutting comprising a frame, a projecting cutter bar, and flexible means for continuously feeding the machine during cutting, of means carried by said frame and movable at a uniform rate with the machine adapted to slidably engage an extraneous abutment during feeding movement of said machine, said means being operative to prevent movement of said machine 100 only upon reverse bodily movement of the latter due to the failure of said feeding means.

5. The combination with a flexibly fed mining machine bodily slidable on its own bottom on the mine bottom during cutting including an elongated frame and a horizontally projecting cutter bar and means for continuously feeding the machine during cutting, of means carried on said frame and movable at a uniform rate with the machine and having a pivot disposed substantially in the plane of the cutter bar, said last mentioned means being adapted to engage an extraneous abutment and automatically operative upon failure of said feeding means to arrest a rearward movement of said frame.

6. The combination with a flexibly fed mining machine bodily slidable on its bottom on the mine bottom during cutting in-

cluding an elongated frame and a projecting cutter bar at one end thereof and means for continuously feeding the machine during cutting, of means movable at a uniform rate with the machine including a sprag pivotally mounted on said frame adjacent said bar and extending upwardly and rearwardly from its pivot and having an abutment engaging point, and resilient means normally holding the point of said sprag in elevated position above the machine frame in floating engagement with the mine roof so that the sprag will substantially instantaneously positively engage the mine roof in a substantially vertical line upon reverse bodily movement of said machine.

7. The combination with a mining machine freely slidable on its own bottom on an inclined mine bottom during cutting having a projecting cutter bar and means for continuously feeding the machine during cutting, including a flexible feeding member, of means movable at a uniform rate with the machine for substantially instantaneously arresting bodily movement of said machine down said inclined bottom upon failure of said flexible feeding member.

8. The combination with a mining machine freely slidable on its own bottom on an inclined mine bottom during cutting having a projecting cutter bar and means for bodily continuously feeding said machine along the inclined bottom during cutting, including a flexible feeding member, of means movable at a uniform rate with the machine including an element pivoted on said machine adjacent the bottom thereof and automatically operative upon an initial reverse movement of the latter for substantially instantaneously arresting bodily movement of said machine down the inclined bottom upon failure of said flexible feeding member.

9. The combination with a mining machine freely slidable on its own bottom on an inclined mine bottom during cutting and having a projecting cutter bar and a bottom plate, and means for bodily continuously feeding said machine along the inclined bottom during cutting, including a flexible feeding member, of means movable at a uniform rate with the machine including an element carried on said machine adjacent said bottom plate and engageable with the mine gallery for substantially instantaneously arresting bodily movement of said machine down the inclined bottom upon breakage or release of said flexible feeding member.

10. The combination with a mining machine including an elongated frame and a projecting cutter bar pivoted on one end thereof, means for securing said bar in different angular positions including a pin and registering recesses in said frame and said bar, a sprag extending upwardly and rearwardly from said frame adjacent said bar, pivot

adapted to positively engage the mine gallery to arrest rearward movement of said machine, means carried in an unused aperture and forming a pivot for said sprag, and resilient means connected between said sprag and said frame.

11. The combination with a self-propelled mining machine having bodily movement in one direction during the cutting operation including means for continuously feeding the machine, of means having an abutment engaging point carried by said machine for automatically preventing excessive movement in an opposite direction, said means being operative only upon said latter movement at any point of said machine movement during the cutting operation.

12. The combination with a coal cutting machine having bodily movement in one direction during the cutting operation including means for continuously feeding the machine, of means carried by said machine adapted to engage an extraneous abutment operative upon movement of said machine in a reverse direction for automatically preventing excessive movement thereof in said reverse direction at any point of said machine movement during the cutting operation.

13. The combination with a coal cutting machine having bodily movement in one direction within certain limits during the cutting operation and means for continuously feeding the machine, of means carried by said machine adapted to engage a fixed extraneous abutment for automatically substantially instantaneously preventing excessive movement of said machine in a reverse direction, said means being operative only upon movement of said machine in a reverse direction at any point between its limits of movement.

14. A safety attachment for use with mining machines comprising a sprag adapted to be pivoted on a machine frame and provided with an abutment engaging point, a spring connected at one end to said sprag by longitudinally movable tension regulating means and adapted at the other end thereof for attachment to a machine frame.

15. A safety attachment for use with a mining machine comprising a sprag adapted to be pivoted at one end on a machine frame and provided at its other end with an abutment engaging point, an adjustable collar adapted to be clamped to said sprag in different positions, and a spring connected to said collar and adapted for connection to a machine frame.

16. A safety attachment for use with mining machines comprising a support interposed between projecting portions on a machine frame, a sprag pivoted on said support and provided with an abutment engaging point, an adjustable collar slidably mounted

- on said sprag and adapted to be clamped thereon in different positions, and a spring connected to said collar and adapted for connection to a machine frame. 20
- 5 17. A safety attachment for use in a mining machine comprising a support including an element adapted to engage an aperture in a machine frame, a sprag pivoted on said support and provided with an abutment engaging point, and a spring connected to said sprag and adapted for connection to a machine frame. 25
- 10 18. A safety attachment for use with mining machines of the longwall type comprising a support adapted to be interposed between the bottom plate of a machine and a projecting portion of a machine frame, a 30
- 15 sprag pivoted at its lower end on said support and provided with an abutment engaging point, and a spring connected to said sprag and adapted for connection to a machine frame. 35
19. A safety attachment adapted to use with mining machines of the longwall type comprising a support including an element passing through an aperture in a machine frame and threadedly engaging a bottom plate of the machine, a sprag pivoted at its lower end on said support and provided at its other end with an abutment engaging point, and a spring connected at one end to said sprag by tension regulating means and adapted for attachment to a machine frame. 35

In testimony whereof I affix my signature.

CHARLES C. SMITH.

Certificate of Correction.

Patent No. 1,642,182.

Granted September 13, 1927, to
CHARLES C. SMITH.

It is hereby certified that error appears in the printed specification of the above-numbered patent requiring correction as follows: Page 1, line 49, for the misspelled word "registereing" read *registering*; page 3, lines 22, 33, and 49, claims 7, 8, and 9, respectively, before the word "including" strike out the comma; and that the said Letters Patent should be read with these corrections therein that the same may conform to the record of the case in the Patent Office.

Signed and sealed this 18th day of October, A. D. 1927.

[SEAL.]

M. J. MOORE,
Acting Commissioner of Patents.
